CIGARETTE-MAKING DEVICE

Frank J. Jurek, Buffalo, N. Y.

Application February 20, 1942, Serial No. 431,671

7 Claims.

(Cl. 131—58)

This invention relates to a device for making cigarettes and particularly to a compact device especially suited to the manufacture of cigarettes by the consumer.

Various devices have heretofore been proposed for making cigarettes on a small scale by the ultimate consumer of the cigarettes but these devices have not in general met with commercial success. Their construction has in general been rather complex and in many cases has involved the use of fabric or other flexible parts subject to failure in use.

The device of my invention is entirely of metal or like relatively rigid material. Its construction is rugged and the device will ordinarily be substantially indestructible in normal use. The arrangement and design of devices manufactured in pursuance to the principles of my invention are such as to greatly facilitate manufacture on a mass production basis.

The cigarette making device of my invention has the marked advantage of being compact in the extreme and may readily be carried in a user's pocket or in a handbag. The device of my invention may be manipulated in the hands of a user with extreme facility and since it is not required that the device be placed upon a table or like supporting surface for use, it may be used wherever the user may find himself when he desires to manufacture one or more cigarettes.

While a single complete and specific embodiment is illustrated in the accompanying drawing and described in the ensuing specification, it is to be understood that the principles of my invention are not limited thereto or otherwise than as defined in the appended claims.

In the drawing:

Fig. 1 is a top plan view of the device;

Fig. 2 is a fragmentary longitudinal cross sectional view taken in a vertical plane and on a somewhat enlarged scale;

Fig. 3 is a transverse cross sectional view taken approximately on the broken line III—III of Fig. 2;

Fig. 4 is a transverse cross sectional view taken approximately on the line IV—IV of Fig. 2; and

Fig. 5 is a detailed transverse cross sectional view through a pair of clamping elements of the device.

Throughout the several figures of the drawing like characters of reference denote like parts and the numeral 10 designates generally a principal body member of the device which in the form illustrated comprises a receptacle having an elongate semi-circular bottom wall portion 11, substantially vertical side wall portions 12 and 13, terminating upwardly in flaring wall portions 14 and 15 respectively.

The left-hand end of the device, as viewed in Figs. 1 and 2, is normally closed by a plug-like

element 16 which is provided with a depending pivot lug 17. For pivotally supporting the plug 16, a pair of bracket members 18 and 19 are secured against the outside of the lower portion of the receptacle 10 and have spaced depending lugs 20 and 21, respectively, for receiving therebetween the pivot lug 17 of the plug 16. Pivotal attachment of the plug 16 may be effected in any convenient manner as by means of the pivot screw 22. The plug 16 seats within the left-hand end of the receptacle 10 and serves to close the lower portion thereof when the plug is in the position illustrated. The plug-like member 16 is further provided with a pair of upwardly diverging arms 24 and 25 which embrace the flaring upper terminal portions 14 and 15 of the container walls when the plug is in the closed position illustrated. Pivotal opening movement of the plug-like element 16 is delimited by the projection 27 formed on the lug 17, which engages the bottom of the container 10 when the plug is pivoted to open position.

Rotatable cigarette forming means are journaled in the plug-like element 16 and comprise a shaft element 30 which has bearing in the plug 16 and is screw-threaded into a cylindrical element 31 which is disposed within the receptacle 10 and adapted to rotate therein with its peripheral portions substantially in contact with the semi-circular wall portion 11 thereof. A suitable manipulating handle portion 32 may be secured to the outer projecting end of the shaft element 30 as by means of a pin 33 or in any other suitable manner. The handle element 32 may be serrated, as shown in Fig. 1, or knurled, or otherwise provided with a convenient gripping surface.

The cylinder 31 carries a pair of elongate clamping elements designated 35 and 36 in the drawing. Both of the clamping elements extend to the right of the cylindrical element 31 substantially the full length of the interior of the container. The inner clamping element 36 is secured rigidly to the cylindrical element by virtue of a fastening pin 38 engaging in a transverse flange 39 formed at the end of the clamping element 36. The cylindrical element 31 is preferably recessed to receive the end of flange 39 of the clamping element 36 and the peripheral portion of the cylindrical element 31 is grooved as at 40 to receive both of the clamping elements.

The outer clamping element 35 has an offset at the end thereof as shown at 42 in Fig. 1. This offset 42 terminates in an end flange 43 which is pivoted to the end wall of the cylindrical element 31 as at 44. The offset pivoting of the outer clamping element 35 provides for slight opening movement of the outer clamp with respect to the inner clamp by limited pivoting about the pin 44. A compression spring 45 provided in a recess in

the cylindrical element 31 acts against the offset flange 42 of the outer clamp 45 and tends to bias the outer clamp to an open position. Opening movement of the outer clamp 35 is limited to a very small amount by engagement of the eccentric curving edge 47 of the end flange 43 against the edge of a recess in which it seats at the end of the cylindrical element 31. Rotation of the cylinder 31 in a counter-clockwise direction, as viewed in Fig. 3, causes the clamp 35 to close against the clamp 36 by engagement of the former against the semi-circular wall of the receptacle 10.

It will appear from the foregoing that the assembly comprising the two clamping elements 35 and 36, the cylindrical element 31, the mounting shaft 30, and the handle element 32 may be rotated in the plug 16 with the result that the clamping elements 35 and 36 will revolve in a path concentric with the semi-circular inner wall of the receptacle 10 and closely adjacent thereto. The entire rotatable assembly may likewise be pivoted about the screw 22 to move the clamping elements to a position substantially outside of the confining lower portion of the receptacle 10, subject to restrictions against unintentional pivoting movement which will presently appear.

At its right-hand end the receptacle 10 is provided with a plug-like element 50 which is provided with an inwardly projecting portion 51 whose lower surface is curved to correspond to the inner surface of the lower semi-circular wall portion 11 and whose upper surface is substantially flat and extends across the interior of the receptacle 10 at about the juncture of the straight wall portions 12 and 13 with the flaring wall portions 14 and 15. The plug 50 is further provided with a pair of side lugs 53 and 54 and a bottom lug 55 which extend adjacent the outer surface of the receptacle 10 and are secured firmly thereto by screws 56 which pass through the respective lugs 53, 54 and 55 and the walls of the receptacle 10 and have threaded engagement with the portion 51 of the plug 50 which is disposed within the receptacle 10.

The plug 50 provides bearing engagement for a shaft 57 which terminates just inside of the portion 51 of the plug 50 in a cylindrical enlargement 58 which is of substantially the same diameter as the cylindrical element 31 at the other end of the device. The opposed inner faces of the cylindrical element 31 and the cylindrical enlargement 58 define the length of the cigarette manufactured by the device in a manner which will presently appear.

The peripheral surface of the cylindrical enlargement 58 is grooved, as at 60, to receive the outer or, as viewed in Figs. 1 and 2, the right-hand ends of the clamping elements 35 and 36. By reason of this engagement, the cylindrical enlargement 58 and the shaft 57 normally rotate with the rotatable assembly comprising the cylindrical element 31, the shaft 30, and the handle 32. The projecting end of the shaft 57 is provided with a manipulating handle portion 61 as in the case of the shaft 30 at the other end of the receptacle.

The portion 51 of the plug 50 which extends within the receptacle has inward extensions 64 and 65 which project at the left from the portion 51, as viewed in Figs. 1 and 2, and overlie the cylindrical enlargement 58. The projections 64 and 65 have their lower surfaces of arcuate form to provide a continuation of the semi-circular interior wall of the receptacle 10 and thereby substantially close the circular confinement about

the enlargement 58 excepting just in the region of the groove 60. It will thus be seen that the clamping elements 35 and 36 cannot be removed from the groove 60 by pivotal movement about the pivot pin 22 excepting when the clamping elements 35 and 36 are substantially at top dead center.

When the clamping elements 35 and 36 are in a top dead center position, their removal from the groove 60 is normally prevented by a projecting nose portion 70 of a latch 71 which is received in a groove in the upper surface of the plug 50 for sliding movement axially of the device. The latch 71 is held against movement from the groove in the plug 50 by a flat plate 72 which is secured against the top surface of the plug 50. A manipulating handle projection 74 is formed at the outer end of the latch bar 71. A spring housing comprising a central casing portion 75 and opposite base flanges 76 is disposed against the plate 72, and both the plate 72 and the spring housing may be jointly secured to the plug 50 by screws 77.

The latch 71 is normally urged to latching position through a spring pin 80 which is fixedly carried by the latch 71 and extends upwardly, through an elongate slot in the retaining plate 72, into the interior of the casing portion 75 of the spring housing, where it engages one end of a compression spring 81 whose other end may bear against a rear wall of the casing portion 75.

With the parts in the position illustrated in the drawing, a cigarette paper or other wrapper is disposed so that one of its longitudinal edges is between the clamp elements 35 and 36. The proper lengthwise position of the wrapper may be ascertained by sighting through an opening 82 formed in the outer clamping element 35. Rotation of either of the handles 32 or 61 to cause counter-clockwise rotation, as viewed in Figs. 3 and 4, will cause the clamp bars to close upon the cigarette paper and firmly engage the same by means of protuberances 90 formed on the outer clamping element 35 and registering recesses 91 formed in the adjacent surface of the inner clamping element 36.

After the entire assembly with the engaged cigarette paper or wrapper has been rotated in a counter-clockwise direction through an angle of approximately 300° from the position illustrated in the drawing, the paper will be disposed in the receptacle 10 in a manner to conform with the semi-circular inner surface of the lower portion 11 thereof and tobacco may conveniently be poured into the receiving wrapper so formed. The wrapper may then be wet at its projecting trailing edge and may be manually wrapped across the outside of the outer clamp element 35 to adhesively engage the outer surface of the leading edge of the wrapper or paper. Alternatively, the device may be given an added rotation in the neighborhood of 90° after filling the wrapper and prior to sealing the same. In this way a better formation may be given to the rolled cigarette and more convenient access to the wrapper for sealing the same is afforded. If the latter procedure is pursued, a further revolution of the clamp bars in the same direction will be effected after sealing of the wrapper until the clamp bars reach a top dead center position. In any event this is the final position for effecting removal of the wrapped cigarette.

At this point the latch 71 may be moved outwardly by manipulation of the projecting portion 74 to remove the nose 70 thereof from latch-

ing engagement with respect to the clamping elements 35 and 36. At this time pivotal movement of the plug 16 carrying the cylindrical element 31 and the clamp bars 35 and 36 will move the free ends of the clamping bars 35 and 36 clear of the latching instrumentalities and permit withdrawal of the cigarette from engagement with the clamping bars 35 and 36 in a lengthwise direction with respect to the clamping elements.

What is claimed is:

1. Cigarette making means comprising an elongate container open at its upper side, a pair of relatively thin elongate clamp bars disposed lengthwise of said container and adapted to lie flatwise against each other in clamping position, resilient means urging said clamp bars to separated position to dispose the marginal portion of a cigarette wrapper therebetween, said clamp bars being disposed for joint revolution in said container with their thin dimensions extending radially with respect to the circle of revolution and the outer clamp element in engagement with the container for retaining the clamp bars in clamping engagement, whereby a wrapper engaged by said clamp bars may be drawn into said container and rolled into circular form, said clamp bars being movable jointly outwardly of said container at one end whereby a completed cigarette may be withdrawn from encircling relation with respect to the clamp bars.

2. Cigarette making means comprising an elongate container open at its upper side, relatively thin elongate clamp means disposed lengthwise of said container and adapted to engage the marginal portion of a cigarette wrapper, said clamp means being disposed for revolution in said container with its thin dimension extending radially with respect to the circle of revolution, whereby a wrapper engaged by said clamp means may be drawn into said container and rolled into circular form, said clamp means being pivoted to said container at one end whereby the opposite end is movable outwardly of said container to withdraw a completed cigarette from encircling relation with respect to the clamp bars, and releasable latch means at said opposite end for preventing outward movement of said clamp means during the cigarette rolling operation.

3. Cigarette making means comprising an elongate container open at its upper side and having its bottom wall of substantially semi-circular transverse cross section, relatively thin elongate clamp means disposed lengthwise of said container and adapted to engage the marginal portion of a cigarette wrapper, means engageable with said clamp means at opposite ends thereof and journaled in the ends of said elongate container, said last mentioned means having manipulating portions extending from the ends of said container to dispose said clamp means for manual revolution by either end thereof in said container with its thin dimensions extending radially with respect to the circle of revolution, said circle of revolution being concentric with said bottom wall and disposed closely adjacent thereto, whereby a wrapper engaged by said clamp means may be drawn into said container and rolled into circular form, said clamp means being movable outwardly of said container whereby a completed cigarette may be withdrawn

from encircling relation with respect to the clamp means.

4. Cigarette making means comprising an elongate container whose bottom wall is substantially semi-circular in transverse cross section, a pair of clamp bars disposed lengthwise of said container and separable to dispose the marginal portion of a cigarette wrapper therebetween, said clamp bars being disposed for revolution about an axis substantially coincident with the axis of said semi-circular wall within said container to draw said wrapper into said container and roll the same into circular form, said clamp bars being pivoted to said container at one end whereby the opposite ends of said clamp bars may be moved pivotally outwardly of said container for removal of a formed cigarette and means for confining said opposite ends of said clamp bars during said axial revolution but releasable to allow said pivotal movement.

5. Cigarette making means comprising an elongate container whose bottom wall is substantially semi-circular in transverse cross section, a pair of clamp bars disposed for revolution about an axis substantially coincident with the axis of said semi-circular wall within said container, said clamp bars being separable to dispose the marginal portion of a cigarette wrapper therebetween to be clamped thereby, said clamp bars being pivoted to said container at one end whereby the opposite ends of said clamp bars may be moved pivotally outwardly of said container for removal of a formed cigarette and means for holding said opposite ends against separation during said axial revolution of said clamp bars.

6. Cigarette making means comprising an elongate container whose bottom wall is substantially semi-circular in transverse cross section, a pair of clamp bars disposed for revolution about an axis substantially coincident with the axis of said semi-circular wall within said container, said clamp bars being separable to dispose the marginal portion of a cigarette wrapper therebetween to be clamped thereby, said clamp bars being pivoted to said container at one end whereby the opposite ends of said clamp bars may be moved pivotally outwardly of said container for removal of a formed cigarette, and releasable latch means at said opposite end for preventing outward movement of said clamp means during the cigarette rolling operation.

7. Cigarette making means comprising an elongate container, a pair of clamp bars extending lengthwise of said container, means mounting said bars at both ends for revolution about an axis lengthwise of said container, said means comprising a rotatable plug adjacent each end of said bars, said bars being pivotally mounted by one of said plugs and releasably retained by the other of said plugs whereby, a cigarette wrapper may be placed with an end thereof between said bars, rotated by either of said plugs to form an arcuate tobacco receiving trough, filled with tobacco, and rotated until its edges overlap, sealed, released at one end, pivoted outwardly of the container at the other end, and the completed cigarette removed from said bars by a longitudinal sliding movement in a direction away from said pivotal mounting.

FRANK J. JUREK.
